UNITED STATES PATENT OFFICE.

EPPA H. RYON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TAKE-UP MECHANISM.

SPECIFICATION forming part of Letters Patent No. 745,026, dated November 24, 1903.

Application filed March 5, 1903. Serial No. 146,270. (No model.)

To all whom it may concern:

Be it known that I, EPPA H. RYON, a citizen of the United States, residing at Worcester, in the county of Worcester and State of Massachusetts, have invented certain new and useful Improvements in Take-Up Mechanism, of which the following is a specification.

My invention relates to a take-up mechanism particularly adapted to be applied to and used on looms for weaving heavy fabrics, such as cotton-duck; and the object of my invention is to provide an improved take-up mechanism or mechanism for rotating the take-up or cloth roll at a gradually-reduced speed as the fabric accumulates on the roll.

My invention consists in certain novel features of construction of my take-up mechanism, as will be hereinafter fully described.

I have only shown in the drawings detached portions of a loom-frame with my improved take-up mechanism combined therewith, sufficient to illustrate the nature of my improvements.

Referring to the drawings, Figure 1 is a side view of my improvements with a portion broken away for the sake of clearness. Fig. 2 is an end view and partial section of the parts shown at the right in Fig. 1 looking in the direction of arrow *a*, same figure. Fig. 3 is, on an enlarged scale, an inner perspective view of the internal ratchet-wheel and gearing and the central pivoted lever and gears detached; and Fig. 4 shows the internal gear-wheel 30 detached and a weight mechanism instead of a spring mechanism combined therewith.

In the accompanying drawings, 1 is a portion of the loom side or frame. 2 is the bottom or driven shaft of the loom, on which is fast a double cam 3. A roll 4 (shown by dotted lines in Fig. 1) on the rocking arm 5, pivoted at its lower end on a stud 5', engages the periphery of said cam 3 and is held in engagement therewith by a spring 6. Supported on the rocking arm 5 is a collar 7, adjustable up or down thereon and adapted to be secured thereto.

To the collar 7 is pivotally secured one end of a connector 8. The other end of said connector is pivotally connected to one arm, 9', of

an angle-lever 9, loosely mounted on a stud 10, secured to the loom-frame at its inner end and having a bearing 10' at its outer end in the bracket or stand 11, bolted to the loom side. (Broken away in Fig. 1, but shown in Fig. 2.) On the arm 9' of the angle-lever 9 on a pin 12 is pivoted a pawl 13, (see Fig. 1,) adapted to engage the ratchet-teeth on the internal ratchet-wheel 14, the hub 14' of which (see Fig. 2) is fast on the extended hub 15' of the pinion 15, loose on the stud 10. (See Fig. 2.)

The pinion 15 is intermediate and meshes with the pinions 16 and 17, mounted on the studs 16' and 17', fast in the oppositely-extended ends of the centrally-pivoted lever 18, loose on the stud 10. (See Fig. 3.) A pinion 19, loose on the stud 10, is secured to the lever 18, in this instance by pins 19'. (See Fig. 2.) The pinion 19 meshes with the intermediate pinion 20, loose on a stud 21 on the loom-frame, (see Fig. 1,) and through pinion 22, keyed on the shaft 23, mounted in bearings on the loom-frame, rotates the shaft 23 and the pinion 24, keyed thereon, which meshes with the gear 25 and rotates said gear 25, fast on the shaft 25' of the take-up roll 25". (See Fig. 2.)

The arm 9" of the angle-lever 9 has pivoted to its outer end the lower end of an adjustable connector 26, (see Fig. 1,) and the upper end of said connector is pivotally connected with the slotted end of an arm 27, loosely mounted on a stud 28. Also mounted on said stud 28 is the hub 29' of the segment-gear 29. Said hub has a shoulder adapted to engage a corresponding shoulder or projection on the hub 27' of the arm 27, (see Fig. 2,) the construction being such that the arm 27 may be freely moved in an upward direction by the angle-lever 9 and the extent of its downward motion be controlled by contact of the said shoulders on the hubs 27' and 29', respectively. It will be understood, of course, that many variations may be made in this specific feature of structure without departing from the spirit of my invention. The segment-gear 29 meshes with the gear-teeth 30', formed on a portion of the periphery of the internal gear-wheel 30, (see Fig. 3,) the hub 30" of

which (see Fig. 2) is loose on the hub 15' of the pinion 15. The teeth on the internal gear-wheel 30 mesh with the two pinions 16 and 17.

5 On the periphery of the internal gear-wheel 30 is a projection or hook 31, (see Fig. 1,) on which is hung or supported a link 32, having attached thereto a short chain 33. The lower end of the chain 33 is connected with one end 10 of the lever 34, centrally pivoted on a stud 35 and having notches 34' on its free end, with which is connected the lower end of a tension-spring 36. The upper end of said spring 36 is attached to an adjustable hook 37, secured 15 to a plate 38, bolted to the loom side. The spring 36 acts to retard the revolution of the gear-wheel 30.

In place of the lever 34 and spring 36 I may use a weighted arm 41, fast on a rock-shaft 42, and a cam-arm 43, also fast on said shaft 42 and connected by a chain 44 with the hook 31 on the internal gear-wheel 30, as shown in Fig. 4. The weighted arm 41, through cam-arm 43 and chain 44, acts to retard 25 the revolution of the gear-wheel 30, the same as the spring 36.

The spring 36 or weighted arm 41 and connected parts act as a yielding controller upon the gear-wheel 30, so as to maintain a substantially uniform tension and winding of the cloth as the roll increases in size.

A holdfast-pawl 39 is pivoted on a pin 40, supported in the stand 11, and is weighted at one end, 39'. The other or engaging end engages the internal ratchet-teeth on the ratchet-wheel 14.

The operation of my take-up mechanism is as follows: The revolution of the cam 3 with the shaft 2 through the roll 4 rocks the arm 40 5 and through connector 8 rocks the angle-lever 9 on the stud 10, and the pawl 13, moving with the angle-lever 9 and engaging the teeth on the ratchet-wheel 14, rotates said ratchet-wheel fast on the hub 15' of the pinion 15 and also rotates said pinion in the direction of arrow *b*, Fig. 1, and through the pinions 16 and 17, meshing with the pinion 15, rotates the lever 18 and the pinion 19, and through intermediate pinions 20 and 22, shaft 50 23, pinion 24, gear 25, and shaft 25' rotates the take-up roll 25" to wind the fabric. As the rotation of the take-up roll 25" causes more of the fabric to be wound thereon, said fabric travels on a constantly-increasing 55 arc of a circle and the take-up roll 25" imparts a gradually-increasing resistance to the operating-gears, which in their turn transfer said resistance to the centrally-pivoted lever 18, having the gears 15 and 16 thereon. 60 This resistance due to increasing size of cloth-roll will cause the internal gear-wheel 30 to revolve against the tension of spring 36 or weighted arm 41, and the teeth 30' thereon, meshing with the teeth on the gear-segment 65 29, will rock said gear-segment on the stud 28, and the shoulder on the hub 29' of said gear-segment will engage the shoulder on the hub

27' of the arm 27 and will act as a stop to hold said arm 27 and prevent the link 26 from dropping down as much, and consequently the 70 pawl 13 will engage less teeth on the ratchet-wheel 14 to rotate said ratchet-wheel. As the internal gear-wheel 30 rotates more, due to the increasing resistance of the take-up roll, the connector 26 will be raised higher and 75 cause the pawl 13 to engage less teeth on the ratchet-wheel 14, with the result that the take-up roll 25" will travel a shorter distance each time. The spring 36, through lever 34 and chain 33, connected to the hook 31, acts as a 80 tension for retarding the revolution of the internal gear-wheel 30. The weighted pawl 39 acts as a holdfast-pawl to hold the ratchet-wheel 14 after it has been partially rotated by the pawl 13. 85

It will be understood that the details of construction of my improvements may be varied, if desired.

Having thus described my invention, what I claim as new, and desire to secure by Letters Patent, is—

1. In a take-up mechanism for looms, a cloth-roll, a stud or shaft, a regulating-gear loose on said stud or shaft, and means for retarding its rotary motion, a rotating arm carrying a pinion fast near its fulcrum, a stud near the free end of said rotary arm and carrying a loose pinion, the said loose pinion adapted to engage both the regulating-gear and driving-gear, and said driving-gear, and operative connections between the driving-gear and cloth-roll, substantially as shown and described. 95

2. In a take-up mechanism, a cloth-roll, a gear on said roll, and means for operating said gear and roll comprising a ratchet, a pawl to turn said ratchet, a regulating-gear, a yielding controller connected with said regulating-gear, and intermediate connections between said regulating-gear and said ratchet-pawl, whereby said pawl is caused to take less teeth of the ratchet as the roll of cloth increases in size, and the strain on the take-up also increases, substantially as shown and described. 110

3. In a take-up mechanism for looms, a roll on which the cloth is wound, a gear on said roll, and means for operating said gear and roll comprising a regulating-gear, a yielding controller connected with said regulating-gear, a ratchet, a take-up pawl, and connections between the said regulating-gear and the said take-up pawl, whereby the movement of the take-up pawl is regulated by the partial rotation of the regulating-gear, against the tension of the yielding controller, substantially as shown and described. 115

4. In a take-up mechanism for looms, a roll on which the cloth is adapted to be wound, means for rotating said roll, said means including a regulating-gear, yielding devices connected to said gear for retarding the rotation thereof and means controlled by said gear for regulating the extent of movement 130

of the roll in accordance with the tension of the cloth as it is wound thereon to maintain a uniform rate of take-up.

5. In a take-up mechanism for looms, a roll on which the cloth is adapted to be wound, means for rotating said roll, said means including a regulating-gear, devices normally acting to retard rotation of said regulating-gear, said gear being rotatable in opposition

to said devices by the tension of the cloth to being wound, and means controlled by the said gear to regulate the extent of movement of the roll to maintain a uniform rate of take-up.
